CLAIM

The ornamental design for a decorative shield, as shown and described.

DESCRIPTION

The decorative shield in which the design is embodied is intended for use by police, military personnel, and other governmental employees during both work and ceremonial functions.

FIG. 1 is a back, perspective view of a decorative shield showing my new design and is drawn at a scale of 0.87 the size of FIG. 2;

FIG. 2 is a front view thereof;

FIG. 3 is a top view thereof and is drawn at a scale of 2.02 the size of FIG. 2;

FIG. 4 is a bottom view thereof and is drawn at a scale of 1.79 the size of FIG. 2; and,

FIG. 5 is a left side view thereof and is drawn at a scale of 0.99 the size of FIG. 2.

The design includes a rectangular sheet of metal having zones of color contrasting with the middle of the shield as seen in FIG. 1, an arm retaining structure with encircling band and handgrip; and a piston with piston driving structure adjacent to the upper side of the arm retaining structure.

The broken lines are included for the purpose of illustrating portions of the shield that form no part of the claimed design.
